UNITED STATES PATENT OFFICE.

THOMAS J. STOCKTON, OF BURKE, VIRGINIA.

ADJUSTABLE FEEDING AND WATERING TROUGH.

1,356,233.

Specification of Letters Patent. Patented Oct. 19, 1920.

Application filed March 10, 1920. Serial No. 364,741.

To all whom it may concern:

Be it known that I, THOMAS J. STOCKTON, citizen of the United States, residing at Burke, in the county of Fairfax and State of Virginia, have invented certain new and useful Improvements in Adjustable Feeding and Watering Troughs, of which the following is a specification.

This invention relates to adjustable feeding and watering troughs, and belongs more particularly to that class or type of troughs which are set up in a fence or like supporting barrier, and arranged to have the food introduced into the trough from one side of the fence, while the creatures to be fed may approach the trough and reach its contents from the other side of the fence, and the trough itself will act in all positions practically as an obstacle to the passage of the feeders from their side of the fence to the other side. This invention also falls within the class of feeding troughs that may be tilted in either direction and secured in different positions, and which may be arranged to feed either large or small stock by suitably changing the position; or it may be so disposed as to enable chickens to obtain convenient access to water or food contained in the trough. This invention begins further with those troughs of the character stated that are provided with a movable and, if desired, removable apron or cover, which is adjustable with the trough and which acts in connection with the trough to constitute an effective means for preventing the stock, especially the small stock, from passing from one side of the fence to the other at the point where the trough is located.

The object of this invention is the production of a trough of the nature mentioned comprising parts of special construction and arrangement whereby it is believed an unusually convenient, durable, easily operated and manufactured feeding and drinking receptacle results.

To illustrate the preferred form and arrangement of the various parts the accompanying drawings are made a portion of this application. Of the drawings Figure 1 represents a short length of fencing to which this invention, shown in side view, has been applied. Fig. 2 is a vertical cross-section of the trough on the broken line 2—2 of Fig. 1, showing the trough in position for feeding large stock, that is to say, the

trough is not tilted. In this view, the apron is shown in its raised position. In Fig. 3 a like section to Fig. 2 is set forth, showing the trough in its lowest position, with the 60 apron also lowered.

Throughout the drawings and description the same letter is used to refer to the same part.

Consider the drawings, the fence A has 65 the posts B and b, which support the trough C by means of its ends D and d, through which pass the trunnions E and e that are secured to the posts as shown in Fig. 1.

It will be noted that the ends of the trough extend higher than the trough itself, and in the rear the ends are connected by the back bar F, usually a piece of angle iron as set forth. To the back bar is secured 70 the rear end of a transverse, curved bracing rib f, the front end of which is secured to the front edge of the trough. The rib f in practice is customarily located about midway between the ends of the trough, but 75 such particular arrangement is not essential. The rib is pierced at different points of its length by bolt holes such as the hole g. A bolt G is supported by the fence rail and is arranged to engage the bolt holes g to 80 hold the trough in different tilted positions as will be readily understood from the drawings.

As best shown in Figs. 2 and 3, the front sides of the ends of the trough are curved 90 circumferentially, with the axis of the trunnions E and e, that is to say, the pivotal axis of the trough, at the center. The rib f has the same curve. Resting upon the curved front sides of the ends of the trough 95 and upon the curved rib is the apron H, which is removable if desired. Along its lower edge are formed spaced openings h to permit the entrance of the heads and necks of small stock or fowls. The apron 100 is provided with a plurality of bolt holes such as the hole J, as shown in Fig. 3, and these holes are so arranged as to enable them to be brought to register with the like bolt holes g through the curved 105 rib f.

The operation of this invention may be most readily explained in connection with Figs. 2 and 3. In Fig. 2 the trough is not tilted. The apron is raised so that large 110 stock may freely feed from the trough. By moving the apron forward additional food

may be introduced from one side of the fence, while the animals remain upon the other side of the fence. In Fig. 3 it will be noted that the apron may be raised until 5 the hole J registers with the hole g, whereupon the bolt G holds both trough and apron together in the adjusted position. Let it be assumed that it is desired to use the trough for a time as a watering trough 10 for poultry. Obviously, it is necessary that the trough be arranged in a low position so that the smaller fowls may reach the food or water. In Fig. 3, the trough is shown as tilted into its lowest position, 15 and releasably held by the bolt G in the bolt hole g. The apron H is also in its lowest position, and in order to secure it in place there may be used a removable pin j passing through the bolt holes of the 20 rib and apron already described. The position of the apron shown in Fig. 3 is the lowest position, and in higher positions, the bolt G is employed to hold both the apron and the trough together in place.

25 Having now described this invention, and explained the mode of its operation, what I claim is:—

1. In an adjustable trough, the combination 30 with a support, of a trough having its ends pivotally connected with the support, the said ends being extended higher than the trough, the front side of each of the 35 said ends being curved circumferentially with the pivotal axis of the trough at the center, a curving bracing rib extending transversely and secured at its forward and to the front edge of the trough, means carried by the trough for securing the rear end

of the rib near the rear edge of the trough between the said ends thereof, the said rib 40 having the same circumferential curve as the said front sides of the ends of the trough, a movable apron resting upon the said rib and the curved sides of the trough, a latching device mounted upon the said 45 support, and openings located at different points of the said rib and of the said apron for engaging the said latching device whereby the trough and apron may be held together in different positions. 50

2. In an adjustable trough, the combination with a support, of a trough having its ends pivotally connected with the support, the said ends being extended higher than the trough, the front side of each end of 55 the trough being curved circumferentially with the pivotal axis of the trough at the center, a back bar connecting the ends of the trough at the rear of the trough, a curving bracing rib extending transversely 60 and having its rear end connected with the said back bar and its front end connected with the front edge of the trough, the said rib having the same circumferential curve as the said front sides of the ends of the 65 trough, a movable apron resting upon the said rib and upon the said curved front sides of the ends of the trough, a latching device mounted upon the said support, and openings located at different points of the 70 said rib and of the said apron for engaging the said latching device whereby the trough and apron may be held together in different tilted positions.

In testimony whereof I affix my signature. 75
THOMAS J. STOCKTON.
